US00D950629S

(12) **United States Design Patent** (10) **Patent No.:** **US D950,629 S**
(45) **Date of Patent:** **** May 3, 2022**

(54) **CAMERA**

- (71) Applicant: **GoPro, Inc.**, San Mateo, CA (US)
(72) Inventors: **John George Muhlenkamp, IV**,
Brisbane, CA (US); **Huy Phuong**
Nguyen, Alpine, UT (US); **Daniel J.**
Coster, Oakura (NZ)
(73) Assignee: **GoPro, Inc.**, San Mateo, CA (US)
(**) Term: **15 Years**
(21) Appl. No.: **29/785,302**
(22) Filed: **May 25, 2021**

Related U.S. Application Data

- (62) Division of application No. 29/706,013, filed on Sep. 17, 2019, now Pat. No. Des. 920,419.

CLAIM

The ornamental design for a camera, as shown and described.

DESCRIPTION

FIG. 1 is a top, front, and left side perspective view of a camera showing our new design;

FIG. 2 is a bottom, rear, and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The equal length broken lines depict portions of the camera that form no part of the claimed design. Additionally, the dash-dot broken lines denote the boundary of the claim and form no part of the claimed design.

1 Claim, 8 Drawing Sheets
